UNITED STATES PATENT OFFICE.

HERMAN WALTHER, OF DAVENPORT, IOWA.

CARBURETER.

1,042,731.

Specification of Letters Patent.

Patented Oct. 29, 1912.

Application filed September 29, 1911. Serial No. 651,977.

To all whom it may concern:

Be it known that I, HERMAN WALTHER, a citizen of the United States, residing at Davenport, in the county of Scott and State of Iowa, have invented certain new and useful Improvements in Carbureters, of which the following is a specification, reference being had therein to the accompanying drawing.

This invention relates to an improvement in carbureters and more particularly to an improved means for controlling the flow of liquid from the gasoline storage chamber to the carbureting chamber.

15 The object of the present invention is the provision in a device of this character of automatic means for controlling the flow of gasoline from the gasoline storage chamber to the carbureting chamber of such a construction that the amount of liquid which is permitted to pass to the carbureting chamber may be readily controlled without the necessity of having access directly to the carbureting chamber.

20 25 A further object of the invention is the provision of improved means for controlling the flow of gasoline from the storage chamber to the carbureting chamber of such a construction as will prevent any danger of 30 the gasoline freezing before passing into the carbureting chamber.

35 40 A further object of the invention is to provide a carbureter in which the valve which controls the passage of fluid from the storage chamber to the carbureting chamber may be readily removed for the purpose of 45 cleaning or repairing the same.

45 Other objects of the invention will be apparent from the detailed description herein- 50 after, when read in connection with the accompanying drawings forming a part here- 55 of, wherein a convenient embodiment of the invention is illustrated and wherein like characters of reference refer to similar parts 60 in the several views.

55 In the drawings: Figure 1 is a vertical sectional view of a carbureter embodying the present invention; Fig. 2 is a fragmentary longitudinal section illustrating the 65 construction of the pipe which connects the storage and carbureter chambers and the 70 valve construction for controlling the flow of liquid through said pipe, and Fig. 3 is a cross section on line 3—3 of Fig. 2.

Referring now more particularly to the drawings, A designates a tank which is adapted to be placed under ground and which is provided with a horizontal partition A' dividing the interior of the tank into an upper or gasoline storage chamber B 60 and a lower or carbureting chamber C.

D designates the air supply pipe which projects into the carbureting chamber and communicates with an air distributing head D', which is adapted to be submerged below 65 the level of the gasoline in the carbureting chamber. The air pipe and distributing head may be of any desired construction and as they form no part of the present invention, I have deemed it unnecessary to 70 describe the same in detail. Communicating with the upper portion of the carbureting chamber is a gas outlet pipe E which may be of any well known construction.

F designates a plug which is provided 75 with a flange f intermediate the ends thereof, the lower end of which is fitted with an opening formed in the partition plate A'. The lower portion of the plug F is threaded upon its exterior and said plug is rigidly 80 clamped to the partition plate A' by means of a clamp nut which is threaded upon the lower portion of the plug and serves to clamp the portion of the partition plate adjacent the opening therein firmly against 85 the collar f of the plug. Threaded upon the exterior of the upper portion of the plug F is a vertically disposed tube G which projects upwardly through the gasoline storage chamber and the upper end of which extends 90 into a suitable box H which is positioned near the surface of the ground. A cap G' is provided for the upper end of the tube G, which cap is removable so that access may be had to the interior of said tube. The 95 lower end of the tube G is provided with a plurality of openings g in the wall thereof which are located just above the top of the plug F and which serve to permit gasoline to flow from the gasoline storage chamber 100 B into the interior of the tube G. The lower portion of the plug F is provided

50

with a counterbore therein in which is threaded the upper end of a pipe I which extends downwardly into the carbureting chamber C, the lower end of said pipe being 5 positioned above the normal level of the gasoline in said carbureting chamber and being provided with a plurality of serrations or notches *i* therein. The plug F is provided with a centrally disposed vertical 10 opening *f*² therein and with a plurality of small vertically disposed ports *f*³ extending therethrough and arranged circumferentially about the opening *f*². The upper surface of the plug F is provided with a concave portion *f*⁴ with which the upper ends 15 of the ports *f*³ communicate and the upper surface of said plug is inclined downwardly from the central portion thereof to the periphery thereof to provide a sharp circular edge around the concave portion *f*⁴ which constitutes a valve seat.

Slidably mounted in the opening *f*² which extends through the central portion of the plug F, is a valve rod K, the upper end of 25 which projects above the top of the plug F and is rigidly connected in any suitable manner to a weight L which is positioned within the pipe G, and the lower end of which projects below the lower end of the pipe I 30 and is threaded into the bottom of a cup-shaped member M which embraces the lower end of the pipe I, the side walls of said cup-shaped member being spaced from the outer surface of the pipe I. The lower end of the 35 weight L is provided with a socket *l* in which is removably seated a valve *l'* of cork or other flexible material which is adapted to coöperate with the valve seat formed on the top of the plug F to prevent the passage 40 of gasoline through the ports *f*³ when the valve is in its closed position.

Rigidly secured to the upper portion of the weight L and extending upwardly in the tube G, is a rod L' which terminates at its 45 upper end in a handle L² permitting rotation of the rod L', weight L, and valve rod K, for a purpose to be hereinafter more particularly set forth.

Formed rigid with the pipe I and projecting laterally therefrom, is a bracket N which is provided at its free end with a depending portion N' to which is pivotally connected a lever O to the long arm of which is connected in any suitable manner, a float O'. The lower portion of the cup-shaped member M is provided with a cleft therein in which is pivotally secured in any suitable manner the short arm of the lever O.

In the operation of the device as thus described, as long as the gasoline in the carbureting chamber is maintained at the proper level, the valve *l'* will be held upon its seat so that no gasoline will pass from

the gasoline storage chamber to the carbureting chamber. As soon as the liquid in 65 the carbureting chamber falls below its normal level, however, the float O' will fall and the lever O will elevate the cup-shaped member M and the valve rod K, thus lifting the valve *l'* off its seat and permitting gasoline to flow from the pipe G through the ports *f*³ in the plug F, into the pipe I and cup-shaped member M. The cup-shaped member M will, as the float lowers, be brought into contact with the lower edge of 70 the pipe I but the gasoline will flow into the carbureting chamber through the serrations *i* formed in the lower end of the pipe I.

The time when the float O acts to cut off 75 the flow of gasoline from the gasoline storage chamber to the carbureting chamber may be varied by adjusting the position of the valve *l'* relative to the cup member M. To effect this adjustment, it is only necessary to remove the cap G' from the upper 80 end of the pipe G and rotate the handle portion L' of the rod L to bring the lower threaded end of the valve rod K out of its threaded socket in the cup-shaped member to any desired extent. This is an important 85 feature of the present invention as the amount of liquid which is to be maintained in the carbureting chamber must vary with the character of the fuel employed and the present construction enables the operator 90 to regulate this amount to a nicety without necessitating his having access directly to the carbureting chamber.

To obtain the best results, it has been 100 found desirable to feed the gasoline from the gasoline storage chamber to the carbureting chamber through restricted ports, but when the gasoline is fed directly into the carbureting chamber in this manner, it has been found that when the apparatus is 105 used in extremely cold climates, the gasoline frequently freezes. With the present construction, this defect is overcome and all of the advantages incident to the feeding of the gasoline through restricted ports, have been 110 preserved, as the gasoline is fed from the storage chamber through the restricted ports, but does not come in contact with the air until it passes through the serrations *i* in the lower end of the tube I and up between the outer wall of the tube I and the side wall of the cup shaped member, and the notches are made of such a size that when the gasoline finally comes in contact with the air, which is at the top edge of the cup-shaped member, that there is a sufficient quantity of gasoline at this point to avoid any likelihood of the same freezing.

While a convenient embodiment of the invention is illustrated in the accompanying 115 drawings, it will be obvious that many 120

changes may be made to the particular form and construction therein shown without departing from the spirit and scope of the invention as defined in the appended claims.

5 I claim:—

1. In a device of the character described, a liquid storage chamber, a chamber adapted to receive liquid therefrom, a pipe depending from the storage chamber into the receiving chamber, a valve controlling the passage of fluid from the storage chamber into said pipe, a cup-shaped member embracing the lower end of said pipe, a connection between said cup-shaped member and said valve, a float lever pivotally supported in said receiving chamber and having one end pivotally connected to said cup-shaped member, and a float connected to the other end of said lever.
- 10 2. In a device of the character described, a liquid storage chamber, a chamber adapted to receive liquid therefrom, a pipe depending from the storage chamber into the receiving chamber, a valve seat adjacent the upper end of said pipe, a vertically movable valve adapted to coöperate with said valve seat, a cup-shaped member underlying the lower end of said pipe, the side wall of said cup-shaped member being spaced from the side wall of the pipe, a rigid connection between said valve and said cup-shaped member, and a float in said receiving chamber pivotally connected to said cup-shaped member.
- 15 3. In a device of the character described, a tank provided with a partition dividing the tank into an upper storage chamber and a lower chamber, a pipe open at its lower end depending from said partition into the lower chamber, a valve controlling the admission of fluid from the storage chamber to said pipe, a cup-shaped member underlying the lower end of said pipe, a rigid connection between said cup-shaped member and said valve, a bracket extending from the pipe depending in the lower chamber, a float lever fulcrumed on said bracket, and a connection between said float lever and said cup-shaped member.
- 20 4. In a device of the character described, a storage chamber, a chamber adapted to receive liquid from the storage chamber, a pipe depending from the storage chamber into the receiving chamber, a valve seat adjacent the upper end of said pipe, a valve for controlling the passage of fluid from the storage chamber to the carbureting chamber, adapted to coöperate with said valve seat, a cup-shaped member embracing the lower end of the pipe depending in the receiving chamber and provided with a threaded socket in its interior, a valve rod extending from the valve and having a

threaded lower end adapted to adjustably engage the threaded socket in the cup-shaped member, means extending without the storage chamber for rotating said valve rod to adjust said valve relatively to said cup-shaped member, and a float in said receiving chamber operatively connected to said cup-shaped member.

5. In a device of the character described, a storage chamber, a chamber positioned beneath said storage chamber and adapted to receive liquid therefrom, a pipe depending from the storage chamber into the receiving chamber, the lower end of said pipe being provided with a plurality of serrations therein, a plug overlying the upper end of said pipe, said plug being provided with a central opening extending therethrough and with a plurality of restricted ports extending therethrough and positioned around said central opening, a vertically movable valve rod extending through the central opening in the plug, a valve carried by said valve rod and adapted upon movement of the valve rod to open and close the restricted ports in the plug, a cup-shaped member secured to the lower end of said valve rod and embracing the lower end of the pipe depending in the receiving chamber, and a float in the receiving chamber operatively connected to said cup-shaped member.

6. In a device of the character described, a tank provided with a horizontally disposed partition dividing the interior of said tank into an upper storage chamber and a lower chamber, a plug secured in the partition in the tank, said plug being provided with a restricted port extending therethrough, a pipe secured at its lower end to said plug and extending through the upper portion of the storage chamber, the lower end of said pipe being provided with a plurality of ports therein, a second pipe positioned in the receiving chamber and having its upper end rigidly connected to said plug, a vertically movable valve rod passing through said plug, a valve carried by said valve rod and adapted to coöperate with the restricted port in said plug, a cup-shaped member adjustably connected to the lower end of said valve rod and embracing the lower end of the pipe in the receiving chamber, means extending from said valve rod upwardly into said first mentioned pipe for operating the valve rod to adjust the valve and cup-shaped member relatively to each other, and a float in the receiving chamber operatively connected to said cup-shaped member.

7. In a device of the character described, a storage chamber, a chamber adapted to receive liquid therefrom, a pipe depending from the storage chamber into the receiv-

ing chamber, a valve controlling the passage of fluid from the storage chamber into said pipe, a cup-shaped member embracing the lower end of said pipe, a rigid connection between said valve and cup-shaped member, a float in the receiving chamber operatively connected to said cup-shaped member, and means extending without the storage

chamber for adjusting said valve and cup-shaped member relatively to each other. 10

In testimony whereof I affix my signature in presence of two witnesses.

HERMAN WALTHER.
